PROTECTOR FOR A CAKE OF SOAP

Alfonso Munoz Arjona, Havana, Cuba

Application September 30, 1957, Serial No. 47,914

Term of patent 14 years

(Cl. D4—3)

Fig. 1.

Fig. 2.

Fig. 3.

Fig. 4.

Fig. 1 is a top plan view of a protector for a cake of soap, showing my new design;

Fig. 2 is a side elevational view thereof;

Fig. 3 is a sectional view taken along line 3—3 of Fig. 1; and

Fig. 4 is a bottom view thereof.

I claim:

The ornamental design for a protector for a cake of soap, as shown.
